RAY P. JACKSON, OF SWISSVALE, AND HAROLD M. SCHEIBE, OF WILKINSBURG, PENNSYLVANIA, ASSIGNEES TO WESTINGHOUSE ELECTRIC AND MANUFACTURING COMPANY, A CORPORATION OF PENNSYLVANIA.

LIGHTNING-ARRESTER.

1,031,796.

Specification of Letters Patent.

Patented July 9, 1912.

Application filed October 8, 1910. Serial No. 586,080.

To all whom it may concern:

Be it known that we, RAY P. JACKSON and HAROLD M. SCHEIBE, citizens of the United States, and residents, respectively, 5 of Swissvale and Wilkinsburg, both in the county of Allegheny and State of Pennsylvania, have invented a new and useful Improvement in Lightning-Arresters, of which the following is a specification.

10 Our invention relates to protective devices and it has special reference to devices known as "horn-gap lightning arresters" and comprising two opposed rods or bars of conducting material which are electrically insulated from each other and are close together at their lower ends and diverge widely at their upper ends.

One of the objects of our invention is to provide a simple and durable lightning 20 arrester of the class above indicated, the opposed parts of which shall be so supported and constructed that the formation of successive electric arcs across the minimum air gap shall automatically cause the members 25 to be separated and thereby interrupt such arcs.

A further object of our invention is to provide means for adjusting the minimum air gap between the two members so that, 30 under normal conditions, it shall exist at a predetermined value, within relatively wide limits.

Lightning arresters of the horn type are particularly well adapted for the protection of high-voltage transmission lines and for other outdoor service on account of their simplicity and reliability, but, if they are used for relatively low voltages, the minimum air gap between the opposed members 35 becomes very small and arcs are sometimes formed in rapid succession, each arc rising to the upper ends of the horns, where it is ruptured. In order to avoid the continuous recurrence of the aforesaid phenomena, we 40 provide opposed members which correspond to the usual horns, but, instead of supporting them near the minimum air gap, we support them near their upper extremities and construct them of strips of unlike 45 metals, or otherwise adapt them to be automatically separated at their lower ends when they are heated. In order to enable the thermostatic members to return to the 50 position which they formerly occupied,

after the electric arcing which caused the 55 heating of the members has ceased, we provide adjustable limiting devices, or stops, which prevent the members from coming so close together as to reduce the minimum air gap below the predetermined value which is 60 necessary to the protection of the circuit or apparatus with which the arrester is associated.

The single figure of the accompanying 65 drawing is an elevation of a lightning arrester constructed in accordance with our invention.

Referring to the drawing, the device here 70 shown comprises two similar opposed members 1 and 2 of conducting material which are relatively close together near their lower ends and diverge until they are materially separated at their upper ends, supporting rods or bars 3 and 4, line insulators 5 and 6, to which the parts 3 and 4 are respectively 75 secured, and stops or limiting members 7 and 8.

The line insulators 5 and 6 may be supported in any suitable manner, being shown 80 mounted on pins 9 and 10 which are carried on a cross arm 11, which, in turn, is carried by a pole or post 12. The members 1 and 2 are composed of straps or bars 13, preferably formed of iron, and other straps or bars 14 of brass or other suitable 85 conducting material having a different coefficient of expansion from that of the parts 13 with which they are associated. The parts 13 and 14 are welded or otherwise secured 90 together to form the arcing members of the device and are bolted to the upper ends of the supports 3 and 4 which extend vertically upward from the insulators 5 and 6 and are bent over at their ends for this 95 purpose.

The strips or bars 13 are bent into U shape at their lower ends, as indicated in the drawing, so that projections 15 are provided to engage adjusting screws 16 of the 100 stops 7 and 8.

The stops or limiting devices are secured to the upper ends of the insulators and project toward each other, their inner ends being bent at right angles to project into the lower U shaped ends of the parts 13. The 105 adjusting screws 16 are mounted in the ends of the limiting strips to engage the projections 15.

If electric arcs are successively formed between the members 1 and 2, the thermostatic properties of the members will cause them to separate, thereby rendering it impossible for more arcs to be formed until the horns have had time to cool and return to their original positions. If then the cause of the disturbance which produces the first arc formed has disappeared, it is evident that the arrester is in condition to protect the line when the next emergency arises.

We claim as our invention:

1. A lightning arrester comprising a pair of initially and variably spaced discharge electrodes that are inherently responsive to the heat generated therein to effect increased separation thereof.

2. A lightning arrester comprising a pair of opposed diverging members the lower ends of which are relatively near together and supports for their upper ends, said opposed members embodying heat-responsive means for causing a separation of their lower ends.

3. A lightning arrester comprising electrically separated vertical supports and a pair of opposed upwardly diverging thermostatic members having their upper ends secured to the upper ends of the vertical supports.

4. A lightning arrester comprising a pair of insulating supports, vertical rods or bars secured thereto and extending upwardly therefrom, a pair of opposed arcing members secured to the vertical rods at their upper ends and converging toward their lower ends, where they are relatively close together, said arcing members being composed of strips of unlike metals, whereby the heat produced by the formation of successive arcs causes the members to separate.

5. A lightning arrester comprising a pair of thermostatic horns supported at their upper ends and stops at their lower ends for limiting the minimum air gap between them to a predetermined value.

6. A lightning arrester comprising a pair of thermostatic horns supported at their upper ends and adjustable stops at their lower ends for limiting the minimum air gap between them to a predetermined value.

In testimony whereof, we have hereunto subscribed our names this 24th day of Sept. 1910.

RAY P. JACKSON.
HAROLD M. SCHEIBE.
